RAILWAY SIGNALING SYSTEM

Filed Aug. 21, 1931

UNITED STATES PATENT OFFICE

HARRY C. VANTASSEL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING SYSTEM

Application filed August 21, 1931. Serial No. 558,481.

My invention relates to railway signaling systems, and has for an object the provision of means operating when a given block is occupied and the signal for such block gives 5 a false proceed indication, to prevent the signal for the block next in the rear from giving a proceed indication.

I will described one form of system embodying my invention, and will then point 10 out the novel features thereof in claims.

The accompanying drawing is a diagrammatic view showing one form of signaling system embodying my invention.

Referring to the drawing, the reference 15 characters 4 and 4^a designate the track rails of a stretch of railway track along which traffic normally moves in the direction indicated by the arrow. These rails are divided by insulated joints 5 to form blocks 1—2, 20 2—3, etc., and, as here shown, each block is further divided by insulated joints 5 to form two track sections, such as 1—1^a and 1^a—2. Each track section is provided with a track circuit comprising a battery 37 which is connected with the rails at one end of the section, 25 and a track relay connected with the rails at the other end of the section and designated by the reference character T with a distinguishing exponent.

30 Located adjacent the entrance end of each block is a signal designated by the reference character S with an exponent corresponding to the location. Each signal, as here shown, is of the searchlight type, comprising a member 6 mounted to oscillate and controlled by two windings 7 and 8. The member 6 carries three roundels G, R and Y, arranged to cooperate with an electric lamp C in such manner that when the member 6 is in its mid- 35 dle position to which it is biased, roundel R is in front of the lamp C, whereas when the member 6 is swung to the left or to the right, roundel Y or roundel G is placed in front of the lamp C. As shown in the drawing, the 40 lamp C is above the roundels, but the lamp is placed in this position for purposes of illustration only, and in actual practice it is understood that the lamp is located directly behind the roundels. The signal indicates "pro- 45 ceed", "caution" or "stop", according as the

roundel G, Y or R is located in front of the lamp C. Operatively connected with the member 6 is a circuit controller comprising two movable members 9 and 10. When the signal is in its stop position contacts 9—9^b and 10—10^b are both closed. (See signal S³). When the signal is in its caution position contacts 9—9^a and 10—10^a are closed. (See signal S²). When the signal is in its proceed position contacts 9—9^a and 10—10^b are closed. (See signal S¹). A signal of the type thus described, is disclosed and claimed in re-issue Letters Patent of the United States No. 14,940, granted to E. J. Blake on August 31, 1920.

55 Associated with each signal is a pole-changing relay P which is supplied with current from a rectifier A as hereinafter explained. Each relay P is preferably slow-releasing in character, so that it will not open 60 its front contacts during a momentary interruption of the current supplied to the relay.

65 Winding 7 of each signal S is constantly supplied with direct current from a suitable source, which is not shown in the drawing, but the terminals of which are designated B and O, respectively. The other winding 8 of each signal is controlled by the track relays for the associated block and also by the relay P for the block next in advance. 70 Referring to signal S¹, for example, the circuit for winding 8 is from terminal B, through front point of contact 13 of relay P², contact 11 of each track relay T² and T¹, conductor 15, winding 8, conductor 16, contact 12 of each track relay T¹ and T², and the front point of contact 14 of relay P² to terminal O. Relay P² being energized, current of what I will term "normal" polarity is supplied to the winding 8 of signal S¹, and 75 this signal then gives its proceed indication. When relay P² is deenergized, and track relays T¹ and T² are both closed, current of reverse polarity will be supplied to the winding 8, and the signal will then give its caution 80 indication. When either track relay T¹ or T² is open, the signal will indicate stop.

85 Each relay P is connected with the output terminals of the associated rectifier A, and the input terminals of this rectifier are con- 90

95 100

nected with the line circuit for winding 8 of the associated signal. Referring to location 1, the input circuit for rectifier A¹ is from conductor 15, through contact 9^a—9 to the lower input terminal of rectifier A¹, and from the upper input terminal of this rectifier through contact 10—10^b to conductor 16. Current of normal polarity being supplied to the line circuit for block 1—2, the upper conductor 15 may be termed the positive conductor, and it will be seen, therefore, that current is being supplied to rectifier A¹ in such direction as to energize relay P¹. Referring now to block 2—3, it will be noted that current of reverse relative polarity is being supplied to the line circuit for winding 8 of signal S², so that the lower conductor 16 of this rectifier may be termed the positive conductor. It will also be noted that signal S² is in the caution position. The input circuit for rectifier A² is then from conductor 16, through contact 9^b—9 to the lower input terminal of rectifier A² and from the upper input terminal of this rectifier, through contact 10—10^a, to the upper conductor 15. It will be seen, therefore, that the circuit controller associated with signal S² functions as a pole-changer to reversibly connect the input terminals of the rectifier with the line conductors 15 and 16, so that current of the same polarity is supplied to the input terminals of the rectifier regardless of the polarity of the current supplied to the line circuit.

Referring now to the block to the right of point 3, which block is occupied by a car or train W, signal S³ indicates stop, because track relay T³ is deenergized. Relay P³ is therefore deenergized, and is placed on short circuit through a path which begins at the right-hand terminal of this relay and passes through the upper right-hand leg of rectifier A³, contact 10—10^b, contact 9^b—9, and the lower left-hand leg of rectifier A³, to the left-hand terminal of relay P. Current of reverse polarity is therefore supplied to the line circuit for block 2—3, with the result that signal S² indicates caution and relay P² is energized. Current of normal polarity is therefore supplied to the line circuit for block 1—2, with the result that signal S¹ indicates proceed.

I will now assume that block 2—3 becomes occupied, thereby deenergizing either track relay T³ or T⁴, but that signal S² gives a false clear indication due to the movable member 6 and the roundels being stuck in such position that the green roundel G is in front of the lamp C. Inasmuch as relay P² receives its energy from the line circuit for block 2—3, which line circuit will then be open at the contacts of either track relay T³ or T⁴, relay P² will be deenergized, so that signal S¹ will give the caution indication. The result will be that a train approaching

signal S² will be traveling at low speed and will therefore be able to stop before entering block 2—3.

I will now assume that block 2—3 is unoccupied, but that signal S² gives a false stop indication due to a mechanical or other failure of the signal. It will be noted that under this condition the relay P² will be disconnected from the line conductor 15 due to the position of the contacts of the circuit controller (see signal S³), so that relay P² will be deenergized and will therefore cause signal S¹ to give the caution indication. In other words, although relay P² is supplied with energy from the line circuit for its associated block, this will not result in a proceed signal immediately in the rear of a signal which falsely indicates stop.

Although I have herein shown and described only one form of signaling system embodying my invention, it is understood that various changes and modifications may be made therein within the scope of the appended claims without departing from the spirit and scope of my invention.

Having thus described my invention, what I claim is:

1. In combination, a railway track divided into blocks, a track circuit including a track relay for each block, a line circuit for each block controlled by the track relay for such block, a signal for each block having a controlling winding receiving current from the associated line circuit and arranged to indicate proceed or caution according as such current is of normal or reverse polarity, a pole-changing relay for each block also receiving current from the associated line circuit, means controlled by each signal for disconnecting the associated pole-changing relay from its line circuit and placing the relay on short circuit when the signal indicates stop, and means for supplying current of normal or reverse polarity to each line circuit according as the pole-changing relay for the block next in advance is energized or deenergized.

2. In combination, a railway track divided into blocks, a track circuit including a track relay for each block, a line circuit for each block controlled by the track relay for such block, a signal for each block having a controlling winding receiving current from the associated line circuit and arranged to indicate proceed or caution according as such current is of normal or reverse polarity, a pole-changing relay associated with each signal, a rectifier for each signal having its output terminals connected with the associated pole-changing relay, a circuit controller operated by each signal for connecting the input terminals of the associated rectifier with the associated line circuit in one direction or the other according as the signal indicates proceed or caution and for disconnecting said

rectifier from the line circuit and placing the rectifier on short circuit when the signal indicates stop, and means for supplying current of normal or reverse polarity to each line circuit according as the pole-changing relay for the block next in advance is energized or deenergized.

3. In combination, a railway track divided into blocks, a track circuit including a track relay for each block, a line circuit for each block controlled by the track relay for such block, a signal for each block having a controlling winding receiving current from the associated line circuit and arranged to indicate proceed or caution according as such current is of normal or reverse polarity, a pole-changing relay for each block also receiving current from the associated line circuit, means controlled by each signal for disconnecting the associated pole-changing relay from its line circuit when the signal indicates stop, and means for supplying current of normal or reverse polarity to each line circuit according as the pole-changing relay for the block next in advance is energized or deenergized.

In testimony whereof I affix my signature.
HARRY C. VANTASSEL.
